ATTORNEY

UNITED STATES PATENT OFFICE.

WILLIAM W. HAYDEN, OF NEWARK, NEW JERSEY

DESIGN FOR A MATCH-BOX.

SPECIFICATION forming part of Design No. 21,611, dated June 7, 1892.

Application filed May 13, 1892. Serial No. 432,933. Term of patent 3½ years.

To all whom it may concern:

Be it known that I, WILLIAM W. HAYDEN, a citizen of the United States, and a resident of Newark, in the county of Essex and State of New Jersey, have invented and produced a certain new and original Design for Match-Boxes, of which the following is a specification.

The accompanying drawing, forming a part of this specification, illustrates my newly-designed match-box or receptacle for small articles.

My new design relates to the ornamentation of the body and top or cover of the box, and the leading feature consists of corrugations covering one of the upper corners of the body and foliated ornamentation in relief occupying the remaining surface and bottom of the body.

A represents the body, and B the top or cover of the box. The upper part of the body shows the parallel corrugations a_1 , while the main lower part is ornamented with sprays or branches $a^2 b$ of leaves, which rise from leaf ornaments $c d$, wrapped around the bot-

tom and edge of the box. The branch a^2 comprises a main stem doubly curved, two upwardly-projecting volutes $e f$, two downwardly-projecting volutes $g h$, and intermediate pointed leaves, while the branch d comprises a doubly-curved main stem, two upwardly-projecting volutes $i j$, the two downwardly-projecting volutes $k l$, and intermediate leaves.

The top or cover B shows at one corner the corrugations a' , and is ornamented in relief with a succession of overlapping leaves m at the edge, terminating in a volute n at one corner, while at the other corner appears the curved leaf o , which reaches beneath the leaves m to the center of the cover, terminating in a volute p .

I claim—

The design for a match-box, substantially as shown and described.

WILLIAM W. HAYDEN.
